SEAL FOR AN AUXILIARY WINDOW FRAME
AND A MAIN WINDOW SASH

Frank Gorell, Penn Township, Allegheny County,
and Peter D. Pozzi, Heidelberg, Pa., assignors
to Aluminum Fabricating Company of Pitts-
burgh, Pittsburgh, Pa., a corporation of Penn-
sylvania

Application July 12, 1950, Serial No. 173,316

3 Claims. (Cl. 20—55)

1

This invention relates generally to double windows and more particularly to an auxiliary window seal that not only seals its own frame, but also seals the main window sash with the main window frame.

The application of storm sash to a permanent window, whether it is applied to the inside or the outside of the window, provides a dead air space between the glazing which functions as an insulation and prevents the collection of moisture in the form of condensation. It is preferable that this air space be connected to the outside air to prevent mist from forming and to permit a very slow change of air. In the storm sash of the prior art more attention is paid to the seal between the storm sash and the permanent window sash than the seal between the permanent window sash and the permanent window frame in which it is hung. Practically every type of window constructed will in time warp to some degree and produce a leak causing a draft.

The principal object of this invention is the provision of a seal for a storm window member that not only seals itself on the permanent window but also seals the permanent sash with its own frame to stop any drafts. If the storm window is mounted on the outside of the permanent window, the storm sash may be constructed to have an independent frame and sash that can open. In a structure of this character the auxiliary frame is sealed with the permanent window sash and the sealing member is extended to seal the permanent sash with the permanent window frame. Regardless of which side the auxiliary window is mounted, the principal feature is to employ the seal of the storm window as a seal between the sash of the permanent window and its frame.

Another object is the provision of a double window seal that is locked in place by the attachment of the auxiliary window member to the main or permanent window.

Other objects and advantages appear in the following description and claims.

The accompanying drawing shows for the purpose of exemplification without limiting the invention and claims thereto certain practical embodiments illustrating the principles of this invention wherein:

Fig. 1 is a sectional view of the auxiliary window and seal.

Fig. 2 is a view showing the structure of Fig. 1 as applied to a main or permanent window, sash and frame.

2

Fig. 3 is a view of a modified form of auxiliary window seal.

Fig. 4 is a view of a metal type of auxiliary seal for windows.

Referring specifically to Figs. 1 and 2 of the drawings, Fig. 1 represents the auxiliary or storm window frame which in this instance comprises an extruded member having the spaced base members 2 and 3 and the intermediate channel member 4 which form the inner mounting face of the auxiliary window. The base member 2 forms the offset 5 with the channel 4 for receiving the sash 6 of the auxiliary window, the glass of which is indicated at 7. The glass 7 is imbedded in the soft elastomer gasket 8, contained within the groove of the sash 6. The auxiliary sash 6 may be hinged to the frame 1 by means of the small pin hinges as illustrated at 10. These hinges may be secured to the frame 1 and to the sash 6 by means of the bolts or rivets indicated at 11 and 12. It is preferable to permit the auxiliary window member to open relative to the sash on which it is hung to provide ready access in cleaning the glass. It is not necessary in most instances to seal the auxiliary sash member with its frame, as it is desirable to have a slight amount of air filter between these members and change the air or condition the air between the two panes of glass. However, when the sash and the frame of the auxiliary window are integral then other means are usually provided to permit a slight amount of influx of air between the glazing of the auxiliary window and the main or permanent window.

The auxiliary frame is provided with the inner mounting face 2, 3 and the perimetral surface 9 forming the corner of the auxiliary window frame. The outer end of the face 3 of the auxiliary frame is provided with a lateral extension 13 that forms a slot or socket 14. The outer end or perimetral face 9 of the extension 13 is provided with a narrow longitudinal groove 15. The seal member 16 is made of any suitable elastomer, such as natural rubber, neoprene, or other synthetic rubber, or a synthetic plastic, and likewise may be an extruded member which takes the shape illustrated. The base 17 of the sealing member 16 fits within the slot 14, and extends around the corner and has a rib 18 provided to fit within the slot 15. The balance of the elastomer member 16 is molded so that it continues the surface of the extension 13, as indicated at 19, to the extension or flexible tip or lip 20. The lip extends from the base of the elastomer member adjacent the corner of the

auxiliary window. The base 17 of the seal extends below the surface of the auxiliary frame 1, as indicated at 21. When the seal is applied to a sash as illustrated in Fig. 2, the flexible extension 20 seals against the frame 22 of the main or principal window and the underside 21 of the base seals against the sash 23 of the main window. Thus, the main window sash 23 is sealed relative to its frame 22 by means of the seal member 16 and no air is permitted to filter beyond or between the flexible sealing member 16 and any other parts that it engages. This closes all the air leaks in the main windows and prevents air from entering the house.

In the extruded auxiliary frame and steel sash and frame structures, as shown in Fig. 2, the seal may be extended around the complete perimeter of the auxiliary frame 1 which extends around the perimeter of the sash member 23 of the main window. The flexible extension 20 likewise engages the frame 22 of the main window for the full circumference of the opening. However, in some cases it is not practical to seal parts of the frame sash with the main frame in which instances the flexible sealing member 16 is continued up to such a point, and the extension may be omitted until the other side of the obstacle where the extension may again take up and continue around the perimeter of the opening. It is not intended to limit this invention to a specific structural cross-section of the auxiliary frame 1 or of the main window sash 23 or the main window frame 22. Many modifications may be made to reconstruct the seal member 16 so as to be adaptable for any particular kind or cross-section of the window structure that is to be employed.

Referring now to Fig. 3 it will be noted that the window frame 25 is an extruded section having the base members 26 and 27 with a lateral extension 28 having the downwardly open slot 29 receiving the elastomer member 30. The elastomer 30 is somewhat similar in shape to elastomer 16. However, it completely fills the open slot 29, and when this member is applied to a window sash, such as illustrated at 31, the whole of the base 32 of the elastomer steel member 30 seals against the surface of the member 31 as illustrated in Fig. 3.

It is obvious from the structures as shown in Figs. 1 to 3 that, when the frame 1 or 25 is fastened or otherwise secured to the sash, a portion of the elastomer seal member is pressed into surface engagement with the sash for the purpose of sealing the same regardless whether the auxiliary window is on the inside or outside of the main or permanent window. Thus, when the main window sash is opened, the frames 1 and 25 are retained in sealing relation with the sash, but when closed the flexible extensions 20 and 30 of the elastomer members 16 and 30 provide an additional seal against the frame of the main window as previously described.

The structure, as shown in Fig. 4, discloses a main window frame member 34 mounted for operation therein a main window sash member 35 and which carries on its outer face the auxiliary frame member 36 which is secured thereto in any suitable manner. The auxiliary frame member 36 is provided with auxiliary sash member 37, being glazed as indicated at 38 providing an air space between the auxiliary and main windows. The auxiliary frame member 36 is provided with an inturned socket 40 raised to receive and retain one end of the seal spring 41,

which may be made of suitable flexible metal such as bronze. The inner end of the metal is secured within the seat 40, and it extends beyond the auxiliary frame 36 and is in engagement with the main sash 35 as indicated at 42. The metal seal has an upward bend 43 and then a downward bend 44, which engages the main frame 34 on the window to seal the same. The double bend 42 and 44 of the flexible seal 41 is retained in sealing engagement with the frame and sash of the main window at all times. When the main window sash 35 is opened the sealing member is carried therewith and may leave its surface engagement with the frame 34 on all sides except that on which the hinges are positioned when the sash 35 is a casement window. However, if the main window structure is that of a double sliding sash then the flexible seal member merely slides along the surface of the main window frame.

An auxiliary window of the character disclosed herein is preferably applied to the exterior of the main windows constructed of wood or steel to protect the surface thereof from the weather and, thus, preserve the painted surface for a longer period of time. However, when applied to aluminum or stainless steel windows, this auxiliary window functions to eliminate the collection of condensation on the windows and still maintain a seal for the primary window sash with its frame.

We claim:

1. A window structure comprising a window sash, an auxiliary window having a mounting face to be secured against said window sash for movement therewith, a substantially continuous slot in the perimeter of said mounting face, a substantially continuous elastomer sealing member having a base portion fitted into said slot and functioning as a sealing cushion when subjected to direct compression between the auxiliary window and said window sash, and an unsupported continuous flexible lip extending from and integral with the base of the elastomer sealing member and extending over the edge of the window sash, said lip being free to flex and seal irregularities of the window structure.

2. A window structure comprising, a window frame defining an opening, a window sash movably mounted on the frame to open and close in said opening, an auxiliary window having a mounting face to be secured against said window sash for movement therewith, a substantially continuous annular slot in the perimeter of said mounting face, a substantially continuous interlocking projection coextensive with and extending beyond said slot, a continuous elastomer sealing member having mating complementary parts fitting the slot and the interlocking projection and providing a continuous pad to function as a cushion and be compressed between the auxiliary window and the window sash to seal therewith and to lock the mating complementary parts in place, and an unsupported continuous flexible lip integral with the elastomer sealing member and extending over the edge of the window sash to be free to flex and continuously engage the frame and seal irregularities of the window structure.

3. A window structure comprising an auxiliary window to be secured against a window sash for movement therewith and having an inner mounting face and an adjacent and outer perimetral surface defining a corner, a substantially continuous slot in said mounting face adjacent said corner, a second slot in said perimetral face ad-

5 jacent said corner, a continuous elastomer sealing member having a base with portions fitting into each of said slots and covering said corner, and an unsupported continuous flexible lip integral with the base of said elastomer sealing member and extending from said base at said corner, said lip being free to flex and seal irregularities of the window structure.
